R. C. HIMEBAUGH.

HAND PLANTER.

APPLICATION FILED AUG. 27, 1914.

1,144,127.

Patented June 22, 1915.

UNITED STATES PATENT OFFICE.

RAY C. HIMEBAUGH, OF BURR OAK, MICHIGAN, ASSIGNOR TO ADELBERT C. HIMEBAUGH,
OF BURR OAK, MICHIGAN.

HAND-PLANTER.

1,144,127.

Specification of Letters Patent. Patented June 22, 1915.

Application filed August 27, 1914. Serial No. 858,862.

To all whom it may concern:

Be it known that I, RAY C. HIMEBAUGH, a citizen of the United States, residing at Burr Oak, county of St. Joseph, and State 5 of Michigan, have invented certain new and useful improvements in Hand-Planters, of which the following is a specification.

This invention relates to hand planters.

The main objects of this invention are to 10 provide an improved hand planter in which the parts are simple and economical to produce and assemble and one which may be collapsed or partially knocked down to better adapt it for shipping and readily set 15 up without tools.

Further objects, and objects relating to structural details, will definitely appear from the detailed description to follow.

I accomplish the objects of my invention 20 by the devices and means described in the following specifications.

The invention is clearly defined and pointed out in the claims.

A structure which is a preferred embodiment 25 of my invention is clearly illustrated in the accompanying drawing forming a part of this specification, in which:

Figure I is a rear perspective view of a corn planter embodying features of my invention. Fig. II is a detailed side elevation 30 of the structure shown in Fig. I, partially collapsed or knocked down. Fig. III is a perspective view of a lever actuating spring. Fig. IV is an enlarged detail section on line 35 corresponding to line 4—4 of Fig. I showing the manner of securing the lever actuating arm to the actuating lever. Fig. V is an enlarged detail section on line corresponding to line 5—5 of Fig. IV. Fig. VI is an 40 enlarged detailed section showing the manner of securing one end of the actuating spring. Fig. VII is an enlarged detailed section on line corresponding to line 7—7 45 of Fig. I showing the manner of securing the other end of the actuating spring.

In the drawing similar reference characters refer to similar parts throughout the several views, and the sectional views are taken looking in the direction of the little 50 arrows at the ends of the section lines.

Referring to the drawing, the staff 1 is channel shaped in cross section and is disposed with the channel facing rearwardly.

In practice, the staff is a sheet metal stamping. The handle 2 is secured to the staff by 55 means of the bolt 3 extending through the handle and provided with a suitable nut, not shown so that it may be readily removed. The hopper 4 is mounted upon the staff above the chute 6 which is also of 60 sheet metal and is arranged with its sides lapping the flanges of the staff and secured thereto by spot-welding, the spot-welding not being indicated. Below the hopper is the usual fixed blade 7 and movable blade 8. 65 The movable blade is secured to the actuating lever 9 which is pivoted to the flanges 10 on the fixed blade at 11. The actuating lever 9 is also a sheet metal stamping, channel shaped in cross section and is disposed 70 with the channel facing forwardly.

The lever is connected to the feed mechanism by the link 12. As the details of the feed mechanism form no part of this invention, they are not further illustrated or described. The actuating arm 13 for the lever 75 9 is formed of a loop of wire, the arms of the loop being curved upwardly and terminating in inwardly projecting pintles 14 engaged in the key hole slots 15 in the 80 flanges of the lever. The pintles 14 have lugs 16 thereon adapted to pass through the narrow portions of slots 15 which are disposed downwardly when the lugs are presented laterally thereto. When the arm is 85 swung to its operative position as shown in Fig. I, these lugs 16 are brought out of register with the narrow portions of the slots and retain the pintles.

The arm 13 is provided with coils 17 at 90 its outer or bight end constituting eyes for the pin-like members 18 of the brace 19. This brace is formed of a loop of wire, its arms terminating in the pins 18. The bight end of the brace is secured to the actuating 95 lever 9 by means of the eye bolt 20. When the brace is disengaged from the arm 13, the arm may be swung up on the outer side of the actuating lever and the brace swung downwardly as shown in Fig. III. The 100 arm 13 is provided with a sheet metal shoe 21. The actuating spring 22 for the lever 9 is U-shaped and has spring coils 23 at its bight. One arm of the spring 22 terminates in an inwardly offset pin 24 adapted to engage a hole 25 in the lever, see Figs. I and

VII. The other arm of the spring terminates in a hook 26 adapted to engage a hole 27 in one of the flanges of the staff. The hook is turned downward and lies on the inside of the flange when engaged. The hook cannot be disengaged without first releasing the spring from the lever so that the spring may be swung forwardly in front of the staff. The pin portion 24 of the spring 10 is held in engagement by the tension of the spring. When the spring is disengaged, it may be placed against the side of the chute 6 as shown in Fig. III, and the parts retained in their collapsed position by means 15 of the cord 27.

By forming and arranging the parts as I have illustrated and described, they are simple and economical to produce and may be quickly assembled as no pivots or retaining rivets are required for the spring or the actuating arm and their connections to each other. The structure also has the advantage of being very durable.

In using the planter the blade 7 is pushed 25 into the ground and the staff rocked forwardly to bring the actuating arm into contact with the ground which, through the connections described, actuates the lever 9, which is connected to the dropping mechanism by the link 12 the dropping mechanism not being shown. The movable blade is, by this movement of the lever, opened, allowing the grain to drop to the ground. When the blades are lifted from the ground 35 the earth falls back upon the grain, covering the same.

Having thus described my invention, what I claim as new and desire to secure by Letters Patent is:

40 1. A planter comprising a channel shaped staff of sheet metal, disposed with the channel facing rearwardly, a channel shaped actuating lever of sheet metal pivotally mounted at its lower end and disposed with 45 the channel facing forwardly, the flanges of said lever being provided with opposed key-hole slots, the narrow portions of the slots being disposed downwardly, an actuating arm formed of a loop of wire, the arms of 50 the loop terminating in inwardly projecting pintles having laterally projecting lugs struck up therefrom, said lugs being adapted to enter the narrow portions of the slots in said lever when presented laterally there- 55 to and to retain the pintles when the arm is swung to operative position, said actuating arm having coils at its bight end constituting brace engaging eyes, a brace formed 60 of a loop of wire pivotally connected to said lever at its bight end, its arms terminating in inwardly projecting portions engaging said eyes on said arm, and a U-shaped spring having a coil at its bight, one arm of said spring terminating in an 65 inwardly offset lever engaging pin and the

other terminating in a hook engaging a hole in one of the flanges of said staff, all co-acting for the purpose specified.

2. A planter comprising a channel shaped staff of sheet metal, disposed with the channel facing rearwardly, a channel shaped actuating lever pivotally mounted at its lower end and disposed with the channel facing forwardly, the flanges of said lever being provided with opposed key-hole slots, 70 an actuating arm formed of a loop of wire, the arms of the loop terminating in inwardly projecting pintles having laterally projecting lugs, said lugs being adapted to enter the narrow portions of the slots in 75 said lever when presented laterally thereto and to retain the pintles when the arm is swung to operative position, a brace pivotally connected to said lever and connected to said arm, and a U-shaped spring, one 80 arm of said spring terminating in a lever engaging pin and the other terminating in a hook engaging a hole in one of the flanges of said staff, all coacting for the purpose 85 specified.

3. A planter comprising a staff, a channel shaped actuating lever pivotally mounted at its lower end, the flanges of said lever being provided with opposed key-hole slots, 90 an actuating arm formed of a loop of wire, the arms of the loop terminating in inwardly projecting pintles having laterally projecting lugs struck up therefrom, said lugs being adapted to enter the narrow portions of the slots in said lever when presented laterally thereto and to retain the pintles when the arm is swung to operative position, said actuating arm having coils at 95 its bight end constituting brace engaging eyes, and a brace formed of a loop of wire 100 pivotally connected to said lever at its bight end, its arms terminating in inwardly projecting portions engaging said eyes on said arm, substantially as described.

4. A planter comprising a staff, a channel shaped actuating lever pivotally mounted at its lower end, the flanges of said lever being provided with opposed key-hole slots, an actuating arm comprising wire side members terminating in inwardly projecting pintles having laterally projecting lugs adapted to enter the narrow portions of the slots in said lever when presented laterally thereto and to retain the pintles when the arm is swung to operative position, and a brace for said arm detachably secured thereto.

5. A planter comprising a flanged staff, an actuating lever pivotally mounted at its lower end, an actuating arm for said lever, and a U-shaped spring having a coil at its bight, one arm of said spring terminating in an inwardly offset pin engaging said lever from its rear side and the other terminating in a hook engaging a hole in one of 125

the flanges of said staff, the bill of said hook being substantially parallel with the arm and lying within the flange of the staff so as to limit the outward lateral movement 5 of the said spring.

6. A planter comprising a flanged staff, an actuating lever pivotally mounted at its lower end, an actuating arm for said lever, and a U-shaped spring, one arm of said 10 spring terminating in a hook engaging a hole in one of the flanges of said staff and the other with a pin engaging said lever from its rear side whereby said pin is retained in engagement with said lever by the 15 resiliency of the spring, said spring being supported against outward lateral movement by said hook.

7. A planter comprising a staff, an actu-

ating lever pivotally mounted at its lower end, an actuating arm for said lever, and a 20 U-shaped spring, one arm of said spring terminating in a hook engaging a hole in said staff and the other with a pin engaging said lever from its rear side whereby said pin is retained in engagement with said lever by the resiliency of the spring, said 25 spring being supported against swinging movement by said hook.

In witness whereof, I have hereunto set my hand and seal in the presence of two 30 witnesses.

RAY C. HIMEBAUGH. [L. S.]
